[57] CLAIM

The ornamental design for a portable animal enclosure, substantially as shown and described.

DESCRIPTION

FIG. 1 is a top plan view of a portable animal enclosure showing my new design;

FIG. 2 is an elevational view taken from one side thereof;

FIG. 3 is an elevational view taken from the side opposite that shown in FIG. 2;

FIG. 4 is a front elevational view thereof; and

FIG. 5 is a rear elevational view thereof.
